TOOTH BRUSH HOLDER

Edward H. Koch, Buffalo, N. Y.

Application January 13, 1934, Serial No. 706,519

7 Claims. (Cl. 312—112.5)

My invention relates to a sanitary, antiseptic container, designed to be attached as a fixture to the wall of a bath or other room for the reception of toothbrushes.

One of the principal objects of my invention has been to provide a device of this nature in which a number of brushes may be conveniently held in such manner as to be protected from dust, offensive odors, and impurities of various kinds, and to preserve them in a clean, dry, sterile condition when the brushes are not in use.

Another object has been to provide a device which will not only be attractive in appearance and convenient to use, but one which may be readily cleansed.

Another object has been to provide a device in which toothbrushes of any size may be held.

A further object has been to provide a device having separate compartments for each brush and also to provide a centrally arranged anti-septic holder which shall be in communication with each of the toothbrush compartments.

Moreover, my invention comprises a flexible disc at the bottom of the device having openings through which the brushes may be conveniently passed, such disc being held in place partly by engagement therewith of suitable lugs carried by the base of the device.

Furthermore, it has been an object to produce a device of relatively few parts, but arranged in such manner that they may be very readily detached for cleansing and thereafter easily reassembled.

Moreover, my device is so designed that adequate ventilation is provided for, so that the brushes will be properly dried out.

The above objects and advantages have been accomplished by the device shown in the accompanying drawing, of which:

Fig. 1 shows a side, sectional elevation of my device taken on line 1—1 of Fig. 2.

Fig. 2 is a plan, sectional view, taken on line 2—2 of Fig. 1 with portions thereof broken away.

Fig. 3 is a perspective view, somewhat reduced, of the partition element of my device.

Fig. 4 is a fragmentary view of one form of disc of my device.

My device comprises a wall bracket 5 having a bracket arm 1 which carries an annular ring member 6, the ring member and bracket support being preferably integral. The bracket is formed with a base 8 having suitable holes for the insertion of attaching screws. The bracket may be made of any suitable material but preferably of a material which may be readily kept clean.

The annular ring member is formed with a sufficient number of inwardly radiating arms 9 which are joined together and to the bracket arm 1 at the center of the ring member, and these arms together with the bracket arm provide a center support for a vial 35, hereinafter described, and also provide the desired number of brush spaces. The ring member is also formed with an annular recess 10, thus providing an annular supporting surface 11.

The device is provided with a casing or cover element 15 which fits down into the recess 10 and is preferably secured to the ring element 6 by means of two oppositely arranged bayonet joints 16. The casing is preferably semi-spherical on the top, as shown, and ventilation is provided for by means of a centrally arranged aperture 17.

Between the supporting surface 11 and the bottom of the casing 15 there is arranged a disc 20. This disc is made of any suitable flexible material, such as rubber, or the like, and it may be provided with a number of diamond shaped openings 21. The openings are preferably so spaced that when the disc is in place, they will be arranged opposite the spaces between the bracket arm 1 and the radiating arms 9. Each of these openings is substantially of such size and shape that it will fit about the handle of a toothbrush and be substantially closed when the toothbrush is in place. It must, however, be capable of enlargement as the brush is inserted up and down through the opening, and for this reason I provide a number of radiating slots 23, one running preferably from each corner of the diamond and one from the side of each of the walls midway between the corners. These slots may terminate in small openings 24 to reduce the tendency to tearing or splitting of the material at the end of the slots. By this arrangement, a plurality of inwardly extended tabs 25 are provided which are easily forced inwardly or outwardly as the bristles of the brush are passed through the disc. The openings are so positioned that they will guide the brushes in such a manner that the bristles thereof will not come in contact with the ring member 6 or the arms 9 or 7.

My device is provided with a partition unit 22, whereby the space within the cover is divided into a number of toothbrush compartments. This partition unit is designed to fit within the casing or cover and to have its edges substantially contact with the wall thereof. The device shown in the accompanying drawing is made for use in connection with four brushes, and, therefore, four

brush compartments are provided by means of the four radiating walls 30 of the partition unit. These walls have their upper edges curved to fit the semi-spherical inner surface of the casing and the bottom surfaces are brought into engagement with the disc 20 substantially in registration with arms 9 of the ring member and bracket arm 7. The parts are so proportioned that the lower edge of the casing and the lower edges of the partition unit will help to retain the flexible disc 20 in place. To further assure that the flexible disc will be properly retained in place as the brushes are passed through the openings of the disc, I provide a pair of interspaced anchoring lugs 31, carried by each of the arms 9 and the bracket arm 7 and arranged at a point thereon which is slightly within the inner periphery of the casing when in place. These lugs have vertically arranged faces 32 which are preferably at right angles to the disc and with curve shaped faces 33 connecting the top edge of the lug with the arm, as clearly shown in Fig. 1. The disc is provided with openings 34 which engage with these lugs and which keep the materials stretched taut across from one side of the device to the other as there is a tendency to stretch it by reason of the passage of the brush through one of the holes. The straight sides or surfaces 32, being oppositely arranged, will prevent the rubber from being pulled off of the lugs. The lugs, as well as providing for the holding of the flexible disc 20 in place, also function as stops for the walls of the partition unit thus assuring that the compartments formed by such walls will not change their position in relation to the openings of the disc. The space between the lugs is such that one of the radiating walls will fit between each pair and thus prevent the partition unit from becoming displaced. The partition unit may be made of any material which is readily cleansed, and I preferably use glass or cellulose composition. Instead of making it of one piece, as is preferable, I may find it convenient to form it of two interlocked pieces.

I provide in my device a centrally arranged antiseptic holder 35 which may be in the form of a glass vial containing a suitable antiseptic or disinfectant. If desired, an absorbent material 36, such as, for instance, absorbent cotton, may be used in the vial for holding the antiseptic or disinfectant. The vial is, of course, open at its upper end, and it is supported in the center of the ring member and held in registering position by means of holding lugs 37. One of these lugs is carried by each of the radiating arms 9 and the bracket arm 7 and has its inner surface 38 curved to fit the vial. These lugs are also passed through suitable apertures 41 formed in the disc and they also aid in holding the disc in place. The partition unit is cut away at its center so as to provide a recess 39 for the reception of the vial 35 and a further recess 40 is provided for passage over the holding lugs 37. The fit between these parts is made as snug as is consistent with the material being used, and passage of any appreciable amount of air from one of the brush compartments to the other is thus prevented. The radiating walls of the partition, being relatively narrow, as shown in Fig. 1, the top of the vial will be open to all four compartments.

In the drawing, I have shown the partition unit and casing or cover, as well as the vial, as made of glass, since this material is highly suitable from a sanitary standpoint, but it is obvious that, if desired, I may use any other suitable material.

which can be formed into shape by molding, or casting, or spinning, or pressing, or the like.

From the foregoing, it will be obvious that any one or more of the brushes may be easily and quickly withdrawn from its compartment or placed therein by passage of the bristles through the diamond shaped opening 21 of the flexible disc, and that, furthermore, there is substantially no communication between the brush compartments, whereby each of the brushes is kept separate and distinct from the other brushes. Since the slots 23 and small openings 24, as well as any space between the walls of the diamond shaped opening 21 and the sides of the brush handle, admits air into the compartment, such air will be circulated up through the compartment, around the bristles of the brush contained therein, and will pass out through the centrally arranged opening 17. Since this opening is also larger than the width of the radiating walls 30 of the partition unit, such opening will bring each of the compartments of my device into communication with the exterior air.

It is also clear from the foregoing that my device comprises but relatively few parts, and when it is desired to clean the device, it is only necessary that the casing 15 be removed by being given a slight rotative movement to unlock the bayonet joint 16, after which the partition may be removed including the vial for easy cleansing. The flexible disc 20 may be easily removed by lifting it from the base and off from the lugs 31 and 37 and cleaned by sterilizing or in any other suitable manner.

In Fig. 4, I show a disc of such size that it will not extend underneath the casing, the lugs 31 being sufficient to hold the disc in place without the aid of the casing. Such a modification is within the scope of the appended claims.

Obviously, other modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

1. A toothbrush holder comprising a bracket having a ring member, a casing carried by the bracket, a flexible disc carried by the bracket and having formed therein a plurality of brush openings, a centrally arranged antiseptic vial within the casing, and holding lugs carried by the bracket for the vial, said holding lugs being arranged around the central axis of the bracket, said disc being formed with openings engageable with said holding lugs, whereby the disc will be held in place, the casing being provided with a centrally arranged opening, whereby the same is ventilated.

2. A toothbrush holder comprising a bracket having a ring member, a casing carried by the bracket, a flexible disc carried by the bracket and having formed therein a plurality of brush openings, a plurality of anchoring lugs carried by the bracket, a centrally arranged antiseptic vial within the casing, and holding lugs carried by the bracket for the vial, said holding lugs being arranged around the central axis of the bracket, said disc being formed with openings engageable with said anchoring lugs and said holding lugs, whereby the disc will be firmly held in place, the casing being provided with a centrally arranged opening, whereby the same is ventilated.

3. A toothbrush holder comprising a bracket

5 having a ring member, a casing carried by the bracket, a flexible disc carried by the bracket and having formed therein a plurality of brush openings, a partition unit mounted upon the disc and within the casing, said partition unit having a plurality of walls equal in number to the openings in the disc for dividing the casing into a plurality of chambers, and a plurality of 10 anchoring lugs carried by the bracket and engageable with apertures formed in the disc, said walls being engageable with the anchoring lugs in such manner that the walls will be fixed against relative rotation with respect to the openings of the disc, the top of the casing being substantially semi-spherical and provided with a central opening whereby all of the compartments are 15 ventilated.

4. A toothbrush holder comprising a bracket having a ring member, a casing carried by the 20 bracket, a flexible disc arranged between the ring member and the casing and having formed therein a plurality of brush openings, a partition unit mounted upon the disc and within the casing for dividing the casing into a plurality of chambers equal in number to the openings in the disc, and an antiseptic vial carried at the center of the 25 ring member and having its upper end in communication with all of the compartments of the device, the upper end of the casing being semi-spherical in form and shape and formed with a centrally arranged opening communicating with each of the chambers.

5. A toothbrush holder comprising a bracket having a ring member, a casing carried by the 30 bracket, a flexible disc arranged between the ring member and the casing and having formed therein a plurality of brush openings, a partition unit mounted upon the disc and within the casing for dividing the casing into a plurality of chambers equal in number to the openings in the disc, an 35 antiseptic vial carried at the center of the ring

member and having its upper end in communication with all of the compartments of the device, and holding lugs carried by the bracket for holding the vial in position, the upper end of the casing being formed with a centrally arranged opening 5 communicating with each of the chambers.

6. A tooth brush holder comprising a bracket having a ring member, a casing carried by the bracket, a flexible disc arranged between the ring 10 member and the casing and having formed therein a plurality of brush openings, a partition unit mounted upon the disc and within the casing for dividing the casing into a plurality of chambers equal in number to the openings in the disc, an 15 antiseptic vial carried at the center of the ring member and having its upper end in communication with the compartments of the device, and holding lugs carried by the bracket for holding the vial in position, the partition element being 20 provided with centrally arranged recesses for the accommodation of the antiseptic vial and the holding lugs, the upper end of the casing being semi-spherical in form and shape and formed with a centrally arranged opening communicat- 25 ing with each of the chambers.

7. A toothbrush holder comprising a bracket having a ring member, a casing carried by the bracket, a flexible disc arranged between the ring member and the casing and having formed there- 30 in a plurality of brush openings, a centrally ar- ranged antiseptic vial within the casing, and a partition unit mounted upon the disc and within the casing for dividing the casing into a plurality of chambers equal in number to the openings of 35 the disc, the central portion of the partition being so formed as to provide a space for the accom- modation and support of the antiseptic vial, the casing being provided with a centrally arranged opening, whereby all the chambers are ventilated. 40

EDWARD H. KOCH.
